UNITED STATES PATENT OFFICE.

JOSEPH WILLIAM WILSON, OF NORTHAMPTON, ENGLAND.

SEWING-MACHINE FOR BOOTS AND SHOES.

1,110,024.

Specification of Letters Patent.

Patented Sept. 8, 1914.

Application filed June 8, 1912. Serial No. 702,542.

To all whom it may concern:

Be it known that I, JOSEPH WILLIAM WILSON, a subject of the King of Great Britain, and resident of 27 York road, Northampton, 5 England, have invented new and useful Improvements in Sewing-Machines for Boots and Shoes, of which the following is a specification.

In sewing machines for boots and shoes it 10 is usual to provide a take-up for the thread and also a device for holding the thread against pulling when the stitch is being drawn tight. The take-up consists of an arm or lever swinging freely on a center and 15 having at its extremity a pulley wheel adapted to bear against the thread on its way to the looper. A spring is provided to press or pull the take-up lever and insure that the slack of the thread shall not hang 20 loosely when released from the tension of sewing. The thread holding device comprises a finger which grips the thread while it rests on one of its guiding rolls.

In connection with the take-up it is difficult 25 to provide a spring which will operate upon the lever above referred to with sufficient promptitude in a high speed machine; and in connection with the thread holder very accurate adjustment is necessary or the 30 thread will be improperly held or not held at all at the right moment in quickly running machines. Various spring contrivances have been suggested for the take-up but according to the present invention a chain or 35 other flexible connection is laid around the boss of the lever arm and connected to the same at one end. The opposite end is connected to a spring which imparts a direct pull on the chain thereby turning the lever 40 on its center in the proper direction and pressing the pulley carried by the arm against the thread in the direction desired. The thread holding finger which is preferably furnished with a yielding nose is operated 45 by a positively actuated cam lever mounted on the same shaft so that the proper adjustment of the finger on the shaft is essential. This is effected according to this invention in a very simple and accurate 50 manner by means of a segmental rack and a worm engaging therewith. The rack is attached to the finger and the worm is carried by the structure on which the finger is pivotally mounted. The exactitude of adjustment of which a rack and worm or screw 55 are capable is well understood. The adjust-

ment having been effected the finger is locked by clamping the socket inclosing its shaft onto the latter by means of a screw.

In the accompanying drawing I have 60 shown a portion of a high speed sewing machine embodying the present improvements.

Figure 1 is a side view, Fig. 2 is a sectional plan of the thread holder adjustment 65 detached.

a is thread which is led in the ordinary way over and under guide pulleys *b c d* to the take-up which consists as usual of a stationary pulley *e*, an auxiliary take-up pulley *f* mounted on a swinging arm *g* and the ordinary take-up pulley *h* whence the thread passes to the sewing mechanism.

In a sewing machine running at a high rate of speed it is particularly necessary that the thread should be held firmly yet lightly 75 while each stitch is being drawn and that the auxiliary take-up should act with sufficient promptitude.

i is the thread holding finger the nose of which is elastically mounted and co-operates 80 with the pulley *d* to hold the thread against endway tension when required. The finger *i* is mounted on a stud or shaft *j* upon which shaft *j* is also mounted the cam lever *k* which is actuated by the cam *l*. The lever *k* 85 is connected to the finger *i* by means of a segmental rack *m* carried by the finger *i* and a worm *n* engaging therewith and carried by the lever *k*. By means of this worm and rack connection not only is the rocking motion of the lever *k* imparted to the thread holding finger *i*, but the angle between the two can be adjusted with extreme accuracy 90 according to requirement.

i* is a screw for clamping the finger and 95 the lever together when the adjustment has been effected. The swing arm *g* of the take-up has connected to the boss *o* thereof, a chain *p*, the opposite end of which chain is attached to the spring *q* and the opposite 100 end of the spring *q* is attached to an adjustable hook carried by a bracket *r* stationary on the framework. There is thus provided a pull on the swinging arm which acts very effectively for the purpose required. 105

With these improvements embodied in a high speed sewing machine some of the difficulties which militate against rapidity of running have been removed.

What I claim and desire to secure by Letters Patent of the United States is:—

In a sewing machine, a thread take-up

consisting of a swinging arm and means for giving to the take-up its spring tendency in the required direction, comprising a flexible connection laid around the hub of the swinging arm and attached thereto, and a spring attached to the end of the flexible connection and to a fixed point, substantially as described.

In testimony whereof I have signed my name to this specification in the presence of ¹⁰ two subscribing witnesses.

JOSEPH WILLIAM WILSON.
